UNITED STATES PATENT OFFICE.

CONRAD REHBEIN, OF DETROIT, MICHIGAN, ASSIGNOR TO THE HAYES MANUFACTURING COMPANY, OF DETROIT, MICHIGAN, A CORPORATION OF MICHIGAN.

PRESS.

1,180,738.

Specification of Letters Patent. Patented Apr. 25, 1916.

Application filed August 23, 1915. Serial No. 46,872.

To all whom it may concern:

Be it known that I, CONRAD REHBEIN, a citizen of the United States, residing at Detroit, county of Wayne, State of Michigan, have invented a certain new and useful Improvement in Presses, and declare the following to be a full, clear, and exact description of the same, such as will enable others skilled in the art to which it pertains to make and use the same, reference being had to the accompanying drawings, which form a part of this specification.

This invention relates to apparatus for forming sheet metal parts such as automobile fenders, automobile seat backs and other sheet metal portions which require a special configuration. The actual forming is done by dies into which the metal is forced or drawn by water under pressure.

The object of the invention is the provision of means to prevent separation of dies under the heavy pressure of water after they have been closed. It is found in actual practice that it is advantageous to allow the dies to withdraw a small fraction of an inch after they have been pressed together. This arrangement results in a gripping of the edges of the metal which is not so positive as where the dies are held together under immense pressure; consequently although the sheet of metal is gripped sufficiently to allow the proper drawing of the metal into the concavity of the forming die, the metal is not gripped so tightly that it precludes all slippage and consequently the sheets of metal are not so frequently torn as where the grip is wholly positive.

In the drawings,—Figure 1 is a side elevation of a hydraulic press embodying my invention. Fig. 2 is a vertical cross section of the same taken on the line A—A of Fig. 1. Fig. 3 is a portion of a vertical cross section showing the dies open and one of the cylinders which operates one of the sliding blocks. Fig. 4 is a top or plan view of one of said hydraulic cylinders and one of the blocks together with a portion of the bed upon which it slides.

a designates the guide post or upright of which there are usually four. Upon these slide the sleeves *b* of the ram *c*. The center of the ram at the bottom is formed into a piston *d* which reciprocates in the cylinder *e*. The piston is driven up by water under pressure which is forced into the bottom of

the cylinder through the intake pipe *f*. The upper face of the ram is provided with a plurality of cross grooves *g* of inverted T-shape in cross section. These allow the bolt heads of the bolts *h* secured to the lower die 60 to be slid into the ram and hence when the nuts on the top of the bolts are tightened, the lower die is securely fastened to the ram at the desired position on the ram. The upper die *i* which is here shown as 65 the female die is similarly secured to the bolster *j* of the press. The dies as here shown are dies for the pressing of crown fenders for automobiles. The male die is the lower, the female die the upper one. The 70 female die is provided with a concavity *k* which is similar to the shape of the crown desired in the finished fender. Air vent holes *z* are provided to prevent the air being trapped in the female die. The male die is 75 provided with a shallow concavity for the distribution of the water underneath the sheet of metal out of which the fender is to be formed. Water is admitted to this shallow concavity through the passage-way *l* of the 80 male die. This passage-way is furnished with water under pressure through the feed-water pipe *m*. This feed-water pipe is made up of two portions which come together in a telescoping joint within the sleeve *n* to accommodate the feed-water pipe to the travel 85 of the ram. This is no part of the present invention and hence is not illustrated in detail. It will be noted that the male die is provided with a pair of rubber insert strips 90 *o*. These form gaskets which grip the sheet of metal and form a liquid tight joint between the metal and the die so as to prevent the escape of the water.

When in operation a sheet of metal coated with a drawing compound is inserted between the male and female dies. Water under heavy pressure is turned into the cylinder *e* and this gradually forces the ram with the male die against the female die. Ordinarily a pressure of about 350 tons is used to raise the ram and bring the dies together. After the dies are brought together water under pressure is turned into the hydraulic cylinder *p* (Fig. 3), the water being allowed to flow through the passage-way *q* into the farther end of the cylinder. This forces the piston in the cylinder toward the press carrying the sliding block *r* under the ram *c*. The water already in the 11

cylinder may be allowed to escape through the passage-way *x* which is controlled by the hand valve *y*. Of course there are various ways of controlling the flow of the fluid from and to the cylinder and I am only describing one that may be used as the specific control of this cylinder is no part of my invention. It will be noticed that the top of the block is slightly beveled as is also the bottom of the ram. This allows the block to readily slide in under the ram and then tightly engage with the same. It is advisable to provide a similar cylinder, piston, and sliding block on the opposite side of the ram. This is shown in Fig. 2. The purpose of these sliding blocks is to securely hold the dies together and resist the enormous pressure of the water forced in between the dies. This pressure usually mounts up to 1500# per square inch before the water is turned off and the dies are opened. If it were not for these sliding blocks or some equivalent arrangement the pressure between the dies would have to be resisted by suitable and greater pressure under the piston of the ram. In this sliding block arrangement, as soon as the block is brought under the ram, the pressure under the piston of the ram can be relieved. When it is desired to open the dies the water under pressure is turned into the passage-way *s* to allow the water to flow into the end of the cylinder *p* near the press and the hand valve *y* is turned to allow the water to drain out of the farther exhaust passage *x*. This causes the piston to travel toward the farther end of the cylinder and carries the block *r* out from under the ram. The ram may then gradually drop down opening the dies and the metal which has been formed into the fender can then be pried out of the female die to which it usually clings.

One very important advantage that I have found to flow from relieving the pressure upon the ram is the lessening of the number of pieces of work that are torn. This is attributed to the fact that with the blocks and ram properly calculated so as not to force the dies together in too positive a fashion, the gripping of the sheet metal is not quite so positive as would otherwise be the case were it necessary to utilize a greater water pressure on the ram than the pressure between the dies. Hence a very small slippage is possible between the gaskets and the sheet of metal, which lessens the possibility of tearing the sheet metal

where the sheet metal is subjected to unusual strains during the drawing operation. 60

For the purpose of illustration I have shown valves controlled by hand wheels for each hydraulic cylinder that operates a sliding block, but it will be readily understood that the valves which control these two cylinders *p* and the valves which control the water which lifts the ram, and the water admitted between the dies to do the forming can all be located at one position where they can be controlled by the operator without moving out of his position. 65

What I claim is:

1. In a press for forming sheet metal by utilizing water under pressure, the combination of a pair of dies formed suitably to receive water under pressure, a ram for carrying the movable die, means for moving the ram and one or more slidable blocks adapted to be slid under the ram when the dies have been brought together by the travel 80 of the ram. 75

2. In a press for forming sheet metal by utilizing water under pressure, the combination of a pair of dies suitably formed for receiving water under pressure between the dies, a ram provided with a piston and intended for carrying the movable die, a fluid-operated cylinder in which the piston of the ram reciprocates and means for engaging the ram to hold the dies from separation 90 after being brought together so that the fluid pressure under the ram can be relieved. 85

3. In a press for forming sheet metal by utilizing water under pressure, the combination of a pair of dies suitably formed for receiving water under pressure between the same, a ram for carrying the movable die, one or more blocks for sliding under the ram to hold the dies together against the separation urged by the water pressure 100 therebetween, one or more fluid-operated cylinders and pistons for controlling the movement of the block or blocks. 95

4. In a press for forming sheet metal by utilizing water under pressure, the combination of a pair of dies suitably formed for receiving water pressure therebetween, a ram for carrying the movable die, said ram having one or more beveled faces on its under surface, means for causing the ram to travel, 110 and one or more beveled-face blocks for sliding under the ram into engagement with the beveled face or faces of said ram. 105

In testimony whereof, I sign this specification.

CONRAD REHBEIN.
